UNITED STATES PATENT OFFICE.

GERD HOBISIEFKEN, OF BURLINGTON, IOWA.

DEVICE FOR USE IN APPLYING LOCKS TO DOORS, ETC.

Application filed March 25, 1926. Serial No. 97,349.

Figure 1 is a perspective view of the invention, partly broken away.

Figure 2 is a perspective view of the invention as applied to the door.

5 Fig. 2^a is a plan view of the same.

Figure 3 is a side view of the invention as applied to the door jamb.

Fig. 3^a is a plan view of the same.

Figure 4 is an edge view of the door jamb 10 with the invention applied thereto.

Figure 5 is a perspective view of a modification of the invention, the main angle plate being shown in dotted lines.

The invention has relation to a device for 15 facilitating the work of carpenters and others in applying mortise locks to doors and in applying the keepers of said locks to the door jambs, and it consists in the novel construction and combination of parts as 20 set forth in the appended claims.

In the accompanying drawings illustrating the invention the numerals 1, 1' designate two similar members of a right angle device formed from a rectangular thin sheet 25 of metal having a right angle bend 5 therein midway of its length. The device is preferably mounted at the upper end of a standard or supporting stick 2 at the proper height, said standard having an adjustable 30 foot 3 having a set screw 4 to fix the adjustment, in order that the height may be varied for doors of different sizes.

The device being applied to the door as 35 shown in Figures 2 and 2^a of the drawings, with member 1 parallel to the side of the door, said member is given a tap with the hammer to cause inward extending point 40 projections 4' thereof to be driven slightly into the side of the door to mark the location of the door knob and of the key hole, the door being then, following removal of the device, bored at the points thus indicated for the door knob spindle and for the key hole.

Before the device is removed member 1' 45 is given a tap with the hammer to cause point projections 6 thereof, of which there is a vertical series, to be driven slightly into the free edge portion of the door to mark the location for the mortise of the lock, the door being bored for mortising along such marking.

In marking the door jamb for the keeper plate, the device is applied to the door after the lock has been applied thereto as in 55 Figures 3 and 3^a of the drawings, and the door closed, the closing of the door causing

point projections 7 of a right angle free-edge flange 8 of the member 1 to be driven slightly into the wood of the door jamb, so that when the door is opened, the device may be applied to the door jamb by matching up the point projections 7 with the markings made thereby as in Figure 4, and the openings 9 in the member 1 or in its duplicate 1', used as a guide for the pencil to mark upon the door jamb the location and size of the openings to be made for bolt of the door, i. e. the lock bolt thereof, and the latch bolt. The reason that the device is applied to the door in this case, is because it is necessary to engage the upper of the openings 9 with the latch bolt, so that when the door is closed, the device will be accurately positioned upon the door jamb.

There being duplicate members 1, 1', and 75 duplicate flanges 8, 8', and all other parts being in duplicate, the device is useful in applying locks and keeper plates to both right and left hand doors and the jambs thereof.

Figure 5 of the drawings shows a modification wherein a standard 2' is provided at its upper end with a device formed from a rectangular thin sheet of metal having a right angle bend 5' midway of its length 85 thereby forming two similar members 10, matching up with the members 1, 1' and upon which the members 1, 1' are adapted to be removably mounted or carried by means of reversely turned top flanges 11 90 thereof. No standard 2 is provided in this case.

The flanges 11 are spaced from the adjacent sides of the members 1, 1' to form 95 grooves into which are adapted to fit closely the upper edges of the members 10, the latter being provided with large rectangular openings 12, matching up with but larger than the individual openings 9 of the members 1, 1', so that each opening 12 surrounds the 100 several openings 9 of each member 1 or 1', whereby, should it be desired to have other members 1, 1' having openings 9 of varying size and location for different sizes of doors, this may be provided for by selecting a 105 device having members 1, 1' having openings 9 of the correct size and location and mounting it upon the carrying members 10.

I claim:

1. Means for facilitating the application 110 of mortise locks to doors consisting of a right angle device of sheet metal, one mem-

ber of which is provided with point projections to mark the location of the door knob and key hole and the other member of which is provided with point projections to mark the location of the lock, the first named member being also provided with openings to mark the location of the locking bolt and latch bolt of the lock upon the door jamb.

2. Means for facilitating the application of mortise locks to doors, consisting of a right angle device of sheet metal, one member of which is provided with point projections to mark the location of the door knob and key hole and the other member of which is provided with point projections to mark the location of the lock, the first named member being also provided with openings to mark the location of the locking bolt and latch bolt of the lock upon the door jamb, and further provided with a free edge right angle flange provided with point projections.

3. Means for facilitating the application of mortise locks to doors consisting of a right angle device of sheet metal having duplicate members one of which is provided with point projections to mark the location of the door knob and key hole and the other of which is provided with point pro-

jections to mark the location of the lock, each member having openings to mark the location of the locking bolt and latch bolt of the lock upon the door jamb and having a free edge right angle flange provided with point projections.

4. Means for facilitating the application of mortise locks to doors consisting of a right angle device mounted at the upper end of a standard and having duplicate members, each of which is provided with a comparatively large rectangular opening, and a second removable right angle device carried by the first named device and having duplicate members, one of which is provided with point projections to mark the location of the door knob and key hole and the other of which is provided with point projections to mark the location of the lock, each member having also openings smaller than and registering with the opening of the first named member to mark the location of the locking bolt and of the latch bolt of the lock upon the door jamb and having a free edge right angle flange provided with point projections.

In testimony whereof I affix my signature.
GERD HOBBSIEFKEN.
